TEMPORARY CONSTRUCTION MOLD

Benjamin Harig, Cincinnati, Ohio, assignor, by
mesne assignments, to William M. Goldsmith,
Cincinnati, Ohio

Application April 16, 1927. Serial No. 184,390

26 Claims. (Cl. 25—131.5)

This invention relates to temporary forms used in plastic construction, particularly reinforced concrete building slabs.

An object of this invention is to provide simple and inexpensive means that may be readily erected and wrecked as well as repeatedly used for effecting uniform distances between concrete joists and the floor next below.

One of the difficulties in attaining the foregoing object has been occasioned by the fact that various of the devices necessary for supporting and sustaining the weight of the plastic mass during the petrification thereof, had to be adjusted and measured with much care and accuracy. This necessitated considerable time and required fairly skilled mechanics. It also created lumber wastage.

An object of this invention is to provide the mechanical elements employed in erecting temporary forms for concrete construction that will substantially reduce the element of time and the amount of exacting work of highly skilled mechanics for attaining the same results, and whereby the lumber wastage is practically eliminated.

These and other objects are attained by the means described herein and disclosed in the accompanying drawings, in which:

Fig. 1 is a fragmental perspective view of a mold within which a concrete beam or girder is to be formed and to which mold are attached devices embodying the invention disclosed herein and utilized for forming the joists that connect beams or girders.

Fig. 2 is a fragmental side elevation, parts shown in section, of a mold formed by using devices embodying the herein disclosed invention. This view is taken on line 2/2 of Fig. 1.

Fig. 3 is a fragmental view on line 3/3 of Fig. 1, and showing portions of the structure shown in Fig. 2, but at right angles thereto.

Fig. 4 is a detailed view of a plate, forming a detail of the invention.

Fig. 5 is a fragmental detailed view.

Fig. 6 is a perspective view showing the soffits and filler strips forming part of this invention.

Fig. 7 is a view showing substantially the manner of supporting the soffits from a blank wall.

Fig. 8 is a perspective view of a collar member shown in Fig. 5.

The mold 10 developed by use of the various boards 11, 12, 13, 14, and 15, is built up in any of the manners or methods common in this art. The boards 11 and 15 are generally called battens and extend transversely of mold boards 12 and 14, at intervals along said boards 12 and 14. It

is customary to provide an I beam 16 or other suitable reinforcement for the concrete and such reinforcement projects into the mold. It is necessary that the mold 10 be accurately placed in relation to the various proposed walls, columns 60 17, and proposed other beams or girders of a building undergoing erection. Accordingly, the mechanics build up the mold 10 with great care and accuracy. In a building of the character under consideration, a plurality of beams or 65 girders are poured in molds such as 10. These beams or girders are spaced and generally extend in parallelism. Between the girders or beams there are provided a plurality of parallel concrete joists. These concrete joists connect the 70 beams and girders developed at opposite ends of such joists and are integral with or supported by such beams. Heretofore, because of the employment of the present known means or forms for providing joists for the purpose indicated, it has 75 been necessary to build up the forms or molds for the joists with the same degree of care and accuracy as was necessary to build up the molds such as 10 for the beams or girders. The invention disclosed herein is intended to effect the 80 same accurate building up of the molds or supports for the joists as was formerly effected, however, making it possible to attain that result by mechanical means that may be assembled and erected by practically unskilled workmen as compared with the character of individuals that heretofore were necessary for doing this type and kind of work.

Along the boards or battens such as 11 and 15 of the mold 10, there are applied suitable supports 18 that may be wooden 2x4's or like members. The distance at which the upper face 19 of the support 18 is disposed below the upper edges 20 of the boards 11 and 15 may be substantially uniform. An edging strip 21 may be secured to the upper edges of adjacent boards such as 14 and 15 for attaining the exact distance at which the face 19 of the member or ribbon board 18 should be disposed below the upper face 22 of the edging 21. The edging strips 21 close the 95 upper ends of the spaces between the battens. At intervals along the support 18 there are mounted soffits 23, that form the bottom surface of the concrete joist to be formed. It is to be expected that there will be some variation in 100 different buildings in the distances at which the beams are disposed, wherefore the soffits 23 and the means associated therewith are adapted to be adjusted to the indicated variations. For accomplishing this purpose the soffits comprise 110

a table member 230 carrying a depending vertical brace 24 that may be secured to the soffit by suitable nails or bolts. Brackets 25 may be used to support the table 230 on the brace 24. At the 5 ends of a soffit table and a brace it is desirable to provide a slot or recess indicated at 26 in Fig. 3. This slot or recess may be effected in any suitable manner, for example, as shown herein by spacing the table member from the upper edge of the 10 brace 24 by inserting suitable shims 231 between the table 230 and leg or brace 24. An inverted U-shaped sheet metal extension 27 is adapted to have the base 28 thereof projected into the recess 26. The extension may be provided with elongated slots 29 in the depending legs 30 thereof, said slots adapted to receive a bolt and wing nut structure 31 carried by the brace 24 for clamping the extension at various degrees of projection in or out of the recess 26. A pin 131 may be carried 15 by the brace 24 and serves to preclude sagging of the extension and soffit. The outer end of the extension, or in other words that portion of the extension projecting from and beyond the recess 26 is provided with a pair of lateral flanges 32 and 33 that are formed by bending the legs 30 at approximately right angles. The base portion of the extension comprises a lap, finger or arm 34 having its lateral edges 35 severed from connection with the flanges 32 and 33. An angle plate 36 that may be of sheet metal, has its longer leg 37 in abutment upon the flanges 32 and 33. The shorter arm 38 of the angle plate 36 lies below and in abutment upon the arm 34 formed upon the base 28 of the extension. The angle plate 35 may be permanently attached to the extension by means of rivets or other suitable means. The shorter arm or leg 38 of the angle plate rests upon a support or ribbon board 18. If desired the L-shaped plate 36 may be dispensed with. A 40 like extension structure may be provided at the other end of the soffit. The thickness of the various members used for mounting the soffit upon the support or ribbon board 18 is such that the soffit when mounted has its upper face flush or in substantially the same plane with the face 22 of the edging strip 21. In order to close the space between the end of the soffit and the mold 10, see Fig. 1, there are provided angle brackets 39 comprising a pair of parallel plate like members 40 and 41 integral with and connected by an intermediate webbing or plate like member 42 extending substantially perpendicular between said members 40 and 41. The members may be provided with suitable apertures 43 through which fastening means such as nails may be driven for securing the angle plates upon the soffits at the ends thereof for bridging the space between the soffits and the mold 10. Between the angle brackets 39 supported on adjacent soffits, see Fig. 45 2, there are inserted filler strips 44 of a thickness substantially identical with the thickness of the table portion 230 whereby a framework results to preclude the escape of wet or mush concrete adjacent the mold 10 and between adjacent soffits. The soffits are adapted to receive suitable metal tiles, forms or members indicated in dotted lines at 45 in Fig. 2. The use of metal tiles in this type of construction is well known and is ancillary to the invention disclosed herein. From 60 the foregoing it should be evident that the soffits may all be mounted in position without the provision of any supporting structure in the nature of shores. In other words the soffits are all supported from the mold 10. Thereafter suitable 65 cross braces 46 may be attached to the brace 24

and suitable shoring 47 may be positioned beneath the cross braces 46 for taking up the weight and load of the concrete when poured over and upon the soffits. When using the temporary structure disclosed herein the shoring 47 supports practically no weight or load until the concrete is poured into the mold or form, wherefore it follows that the shoring may be expeditiously mounted beneath the soffits. By reference to Fig. 5 it is evident that the cross braces or 80 stringers 46 may be held in position below the brace 24 by means of collar 48 comprising angle irons 480 and 481 receiving the brace or stringer 24 between the vertical arms 49 and 490 thereof and to the base of which are attached suitable angle irons 50 and 501 for providing between them a way into which the brace member or stringer 46 may be received. A perspective view of this structure is shown in Fig. 8. Suitable fastening means such as nails may be used to 85 attach the members 48, 24, and 46, to one another. If desired a suitable block 51 may be nailed upon the shoring 47 and the cross support 46, although in practice it has been found unnecessary to provide a block 51. In building up 90 the joist molds, the collar members 48 may be fastened to the brace 24 of the soffit. Thereupon the stringers may be attached to the collar members, and then the shoring may be placed below and in contact with the stringers. This method 95 of construction and assembly effects rapid construction of the joist mold.

On some occasions it may be desired to provide cross bridging intermediate the soffits as shown in Fig. 6. At such places, a filler strip such as 100 44, carrying angle brackets at its end would be inserted between and supported from adjacent soffits, the tiles or pans being capped at such places, wherefore a cross joist of concrete would be molded at such place.

In some installations, the soffits may be supported at an end by means other than a beam mold such as 10. For example, the concrete joists may terminate at one end upon a brick wall as disclosed in Fig. 7. Under such circumstances the ends of the soffits would be supported in substantially the manner shown herein, however, the ribbon board 18 would be supported by a structure other than a beam mold, for example shoring and stringers that would be built up 115 along a wall at which the joists would terminate. In view of the disclosures herein, the suggested structure becomes readily obvious to those skilled in the art. In some instances the shoring or support means other than a beam mold, brick 120 wall, or ribbon board may be provided for establishing the means upon which the extensible ends of the soffits may rest.

Although the soffits shown herein comprise a table 230 and brace 24, it is readily evident that 125 the table portion of the soffit may be dispensed with, and that the body or brace portion may constitute the soffit proper and may carry suitable extensible means or parts that function as do the extensions 27. Accordingly the soffit 130 member that may be employed may be properly termed an extensible joist.

What is claimed is:

1. The combination with a pair of spaced girder molds, supports mounted along the sides of 140 the molds, spaced soffits comprising a depending brace and extension members at the ends of the soffits and contacting the supports at opposite ends of said soffits for aligning the upper faces of the soffits with the upper edges of the molds, 145

- means extending between the soffits and the molds for extending a continuous surface between the ends of the soffits and the mold and in substantial alignment with said upper surfaces 5 of the soffits and mold, and members extending between adjacent soffits and closing the spaces between such soffits.
2. The combination with a pair of spaced girder molds, supports mounted along the sides of 10 the molds, spaced soffits comprising a depending brace and extension members at the ends of the soffits and contacting the supports at opposite ends of said soffits for aligning the upper faces of the soffits with the upper edges of the molds, 15 means extending between the soffits and the molds for extending a continuous surface between the ends of the soffits and the mold and in substantial alignment with said upper surfaces of the soffits and mold, framing 20 members supported by said last mentioned means on adjacent soffits and contacting the molds, said framing members having their upper faces aligned with the upper faces of the soffits and with the upper edges of the molds, and members 25 extending between adjacent soffits and closing the spaces between such soffits.
3. An extensible soffit comprising a table member and a depending leg member, together having a T-shaped cross section, the soffit having 30 a recess at its end and between the table and leg members, an inverted U-shaped extension having its base received in said recess for adjustment longitudinally of the soffit, the legs of the extension depending and lying along the 35 leg member, means for clamping the extension on the soffit, the extension legs comprising outwardly projecting flanges extending in substantial parallelism from opposite sides of the extension, the extension base comprising a finger extending in alignment with the base, and an L-shaped plate having its one leg in abutment on the finger on the base and having its other leg in abutment on the flanges on the legs of the extension, the L-shaped plate adapted to serve 40 as a support for upholding the end of the soffit when disposed upon a suitable support ledge.
4. The combination with spaced temporary beam molds, of lengthwise adjustable parallel spaced soffits supported at their ends between 45 said molds, framing between the ends of adjacent soffits, and means for closing the spaces between the soffits and framings, said last mentioned means, soffits and framings providing extended joist molds over said soffits, merging with the beam molds for providing monolithic concrete beams and joists.
5. The combination of mounted, spaced support members, of lengthwise adjustable parallel spaced soffits supported at their ends between 50 said support members, and means supported by said soffits and closing the spaces between said soffits and support members for providing extended joist molds over said soffits for forming monolithic joists and floor slabs.
6. The combination of mounted, spaced support members, lengthwise adjustable parallel spaced soffits having extensions at their ends for contacting upon the support members for suspending the soffits from said support members, 55 framing between the soffits and supported by and between the soffits, tiles supported by the soffits and forming with said soffits and framing a single mold for a monolithic slab and depending concrete joist structure, said soffits comprising a table and a depending brace, collar 60 members comprising two pairs of angle irons, an arm of each of one pair of angle irons extending in parallelism on opposite sides of the soffit braces, the other arms of said pair of angle irons disposed in the same plane and resting 65 upon an arm of each of the second pair of angle irons, said second pair of angle irons extending at right angles to said first pair of angle irons and having their respective second arms depending in substantial parallelism with one another, 70 whereby a way is provided between them, stringers received and held in said way, and shoring below said stringers for supporting a load the weight of which is directed upon the soffits and stringers.
7. An extensible soffit comprising a bracket and a table member, an inverted U-shape extension having elongated slots in the arms thereof, the bracket received between the arms, and a pair of support means extending through the 75 bracket and into the slots for retaining the bracket and extension in substantial alignment.
8. An extensible soffit comprising a main portion, having a top and sides, an extension portion for adjustment along the main portion and comprising a section disposed adjacent to and in substantial continuity with the top of the main portion, and a side section disposed adjacent one of the sides of the main section, and means for securing the sides of the main portion and extension portions upon one another at various adjusted positions.
9. A mold comprising side members, soffits adjustable longitudinally between said side members, complementary means carried by the side 80 members and soffits for supporting the soffits from said members during the initial erection of said soffits, and shoring below the soffits for supporting the weight of plastic deposited on the soffits.
10. The combination with spaced temporary beam molds, of lengthwise adjustable parallel spaced soffits supported at their ends between said molds, and means for closing the spaces between the soffits and beam molds, said last 85 mentioned means, and soffits providing extended molds merging with the beam molds for providing monolithic concrete construction.
11. The combination of mounted, spaced support members, soffits supported by the support 90 members and extending transversely therebetween, stringers below the soffits, and means for transversely supporting the stringers from the soffits.
12. In a concrete joist mold the combination 95 of spaced soffits, a pair of brackets each comprising parallel oppositely extending platelike members and a connecting member between them, each bracket having one of its upper platelike members disposed upon one of the soffits, and a filler strip supported upon the lower platelike members and connecting the soffits.
13. In a concrete joist mold the combination 100 of spaced soffits, a filler strip and mounting therefor, and comprising a filler strip having substantially parallel opposed faces, and a pair of brackets, a bracket mounted at each end of the filler strip and comprising each a pair of substantially parallel platelike members extending in opposite directions supported by the soffits and connected to a central member abutting the end of the filler strip, each bracket having a platelike member extending over a portion of the filler strip, said last mentioned platelike 105

- members extending toward one another on a common side of the filler strip.
14. An extensible soffit comprising a body, an inverted U shape extension slidably lengthwise of the soffit and at the end thereof, and means for securing the body and extension at various positions of adjustment. 80
15. An extensible soffit comprising an elongated body, an extension member adjustable longitudinally of the body at an end thereof and comprising a support ledge, and means for securing the body and extension upon one another at selected positions of adjustment. 85
16. An extensible soffit comprising a body portion, an inverted U shape extension having elongated slots in the arms thereof, the body portion received between the arms, and a pair of support means extending through the bracket and into the slots for retaining the bracket and extension in substantial alignment. 90
17. The combination of mounted, spaced support members, of lengthwise adjustable parallel spaced soffits supported at their ends between said support members, cross bridging between said soffits and means supported by said soffits and closing the spaces between said soffits, cross bridging and support members for providing an extended mold over said soffits and cross bridging for forming monolithic slabs. 95
18. The combination of spaced support members, lengthwise adjustable parallel soffits supported at their ends between said support members, and means supported by the soffits and closing the spaces between the soffits and support members for providing a mold over said soffits and space closing means for forming a monolithic slab. 100
19. In combination, an elongated construction element of rectangular form in cross-section, a support at right angles to said element and spaced a substantial distance from an end thereof, and a hanger embracing said end portion of the element and engaging substantially spaced apart top and bottom portions thereof and projecting longitudinally beyond said element end portion, the longitudinally projecting portion of said hanger resting on said support. 105
20. In combination, an elongated elevated joist, a fixed support at right angles to said joist and spaced a substantial distance from one end thereof and having its supporting surface on a level above that of the lower surface of the joist, and a longitudinally adjustable hanger embracing a substantial length of said end portion of said joist and having spaced-apart upper and lower transverse portions engaging respectively spaced upper and lower portions of the joist, said hanger having a longitudinally projecting outer end portion of less height than said joist and resting on said supporting surface. 110
21. The combination with spaced parallel girder molds, of a temporary deck for forming concrete ceiling and floor slabs and comprising soffits, each having a table member and a brace member secured thereto at right angles there- 115
- with and extending beyond the ends of the table member, the end of the brace members being secured to the girder molds, and means on the brace members for increasing the length thereof, panel members equal in length to the length of or to a unit of the length of the table members and supportable upon the table members and means cooperating with the panel and table members adjacent the girder molds for filling interstices resulting between the molds and the positioned deck members. 120
22. A filler strip for use with temporary construction forms and comprising a board and an angle strip positioned along an edge thereof, said angle strip comprising a plate adapted to be secured to a supporting element of a temporary construction, and means integral with the plate and abutting the edge and adjacent surfaces of the board for supporting the board. 125
23. The combination of spaced girder forms, soffits supported by the girder forms, decking means substantially filling the spaces between the soffits and girder forms, and filler strips comprising flat elements with angle strips thereon, said filler strips being attachable to the soffits for filling spaces between the decking means and the girder forms. 130
24. The combination with spaced girder forms, of a temporary deck comprising spaced soffits having table members with brace members attached thereto and extending beyond the ends of the table members, means at the ends of the brace members for attaching the soffits to the girder forms, rigid panels each disposed upon the table members of adjacent soffits and substantially filling the spaces between the soffits, and means for insertion at the ends of the table members and along the panels for filling the spaces resulting adjacent the girder forms and between the girder forms, the table members and the panels adjacent thereto. 135
25. The combination with spaced supporting members, of paneling sections adapted to be positioned between said members and having angle strips thereon for attaching the paneling to the supporting members, said strips comprising plate portions attachable to the supporting members and lugs for holding the paneling, the plate portions being adapted to be superimposed and to have superimposed thereon the similar plate portions of angle strips on adjacently positioned paneling. 140
26. The combination with spaced supporting members providing limited supporting surfaces, of paneling adapted to be positioned between and supported upon said members, the paneling having angle strips comprising plate portions for attachment to one of said limited supporting surfaces and lugs for attachment to the paneling, said plate portions being adapted to be superimposed upon and to have superimposed thereon the similar portion of adjacently positioned paneling. 145

BENJAMIN HARIG.
